[57] CLAIM

The ornamental design for a novelty plaque or the like,
as shown and described.

DESCRIPTION

FIG. 1 is a front elevational view of a novelty plaque or the like showing my new design.

FIG. 2 is a perspective view thereof showing the top

FIG. 3 is a back elevational view thereof.

FIG. 4 is a left side elevational view thereof.

FIG. 5 is a perspective thereof in an alternate position and showing the bottom and right-hand side thereof.
